AUDIO VISUAL CARTRIDGE

Paul D. Catalano, Manhasset, and George C. Hoehne,
Bellerose, N.Y., assignors to Retention Communications
Systems, Inc., New York, N.Y.

Filed Dec. 14, 1970, Ser. No. 26,497

Term of patent 14 years

Int. Cl. D14—02

U.S. Cl. D26—14

FIG. 1 is a front perspective view of the audio visual cartridge showing our new design;

FIG. 2 is a rear perspective view of the audio visual cartridge; and

FIG. 3 is a side elevation view of the audio visual cartridge.

We claim:

The ornamental design for an audio visual cartridge, as shown.
